(57) **CLAIM**

The ornamental design for a hand-held receiver, as shown and described.

DESCRIPTION

FIG. 1 is a perspective view of a hand-held receiver;

FIG. 2 is a front view thereof;

FIG. 3 is a left side view thereof;

FIG. 4 is a right side view thereof;

FIG. 5 is a rear view thereof;

FIG. 6 is a top view thereof; and,

FIG. 7 is a bottom view thereof.

The broken line showing forms no part of the claimed design, and the shading is provided to illustrate contour only and is not an indication of texture, gloss, etc.

1 Claim, 5 Drawing Sheets
